UNITED STATES PATENT OFFICE.

HENRY ROBERTS, OF HARTFORD, CONNECTICUT.

WOVEN-WIRE BED.

SPECIFICATION forming part of Letters Patent No. 451,522, dated May 5, 1891.

Application filed December 27, 1887. Serial No. 259,151. (No model.)

To all whom it may concern:

Be it known that I, HENRY ROBERTS, of Hartford, in the county of Hartford and State of Connecticut, have invented certain new and 5 useful Improvements in Woven-Wire Beds, of which the following is a full, clear, and exact description, whereby any one skilled in the art can make and use the same.

The object of my invention is to provide 10 means for attaching woven-wire or like extensible spring fabric to a bed-frame by devices that provide for the forcible stretching of the fabric lengthwise, and also to provide a woven-wire fabric in a form that will enable 15 the manufacturer to dispense with the side rails that are usually present in the bed-bottom as it leaves the factory and to produce a fabric in a light form convenient for packing and shipment.

20 My invention consists in the combination of an extensible woven-wire fabric, end rails secured to the fabric, the folding arms borne on the end rails, and the attaching devices; and it further consists in the details of the 25 several parts of the structure and their combination with a bedstead-frame, as more particularly hereinafter described, and pointed out in the claim.

Referring to the drawings, Figure 1 is a detail view, in central lengthwise section, of a bed-frame and of the woven-wire fabric, with part indicated in dotted outline, and illustrating the method of operation of my improvement when one end rail is attached to the 35 side bars of the frame and the other end rail only is provided with toggle-arms. Fig. 2 is a detail top view of the parts shown in Fig. 1. Fig. 3 is a detail plan view of one of the end rails with the connected arms. Fig. 4 is a detail view of the reverse side of the end rail, showing the arms folded. Fig. 5 is a detail view, on enlarged scale, of the anchor-block and of the end rail removably connected thereto by studs. Fig. 6 is a detail perspective view, on enlarged scale, of the anchor-block.

In the accompanying drawings, the letter *a* denotes what I will term the "mattress," this being preferably made of woven-wire, in the 50 manner well known in the art for producing woven-wire mattresses, and the opposite ends of this mattress *a* are secured to the end rails

b b' in any convenient manner, as by clamping them between the two parts of the rail. In this form such a mattress may be conveniently stowed for shipment by rolling it up on the end rail, and is comparatively light, the side rails of the frame, to which such a mattress is usually secured in the trade, being dispensed with until the mattress is put directly in use, when the side rails of the bedstead-frame are made to serve that purpose. The ends of one end rail are provided with the broad-headed studs *c*, that fit into the dovetailed locking-slot *k'* in the anchor-block *k*. The other end rail *b'* bears two arms *e'*, pivoted to the under side of the rail at the opposite ends in such manner as to permit them to be folded up lengthwise of the end rail very compactly, as shown in Fig. 4 of the drawings. Each of these arms is provided on its outer end with the key-hole slot *d'*, by means of which the arm may be removably secured to the studs *f* by slipping the arm onto the broadened head of the stud *f* and then sliding the arm lengthwise. In attaching this mattress to a bedstead or other frame the arms are secured, as by the means described and as shown in Figs. 1 and 2, to the ends of the end rails of the mattress and with the inner ends of the arms pivoted to the studs *f*, the arms having an angular position with reference to the plane of the frame, while the other end rail of the mattress rests upon and is secured to the anchor-blocks *k*. The other end of the mattress is then depressed by pushing down on the end rail *b'*, and as it approaches the plane of the frame, a spring-tension is put upon the mattress, the distance between the studs *f* and end rail *b* being such that the distance between the end rails when one of them is in the raised position, as shown in Fig. 2, is less than when the said end rail is depressed so as to lie in or near a plane passing through the end rails and points of support *f*. When in the latter position, the fabric is tightly stretched between the end rails, which may be held in this position by any desirable means.

The several locking-slots in each arm are provided so that the end rails may be adjusted at a greater or less distance from each other, so as to provide for the needed degree of stretching of the fabric to secure the proper

tension when in place when held in a frame ready for use.

I claim as my invention—

In combination with a bedstead-frame *g*, having the side rails with anchor-blocks *h* and studs *f*, the elastic fabric composed of interwoven spirals of wire, the end rails secured to the opposite ends of the fabric, the one rail having the locking-studs fitting the slot in

the anchor-block and the other end rail bearing the folding arms, and the arms pivoted to the under side of said end rail and having in their outer ends the key-hole slots, all substantially as described.

HENRY ROBERTS.
